P. HAAS

FROSTPROOF CLOSET VALVE

Filed May 22, 1924

Philip Haas
By his Attorney
John Howard Whitaker

UNITED STATES PATENT OFFICE.

PHILIP HAAS, OF DAYTON, OHIO.

FROSTPROOF CLOSET VALVE.

Application filed May 22, 1924. Serial No. 715,010.

To all whom it may concern:

Be it known that I, PHILIP HAAS, a citizen of the United States, residing at Dayton, in the county of Montgomery and State 5 of Ohio, have invented certain new and useful Improvements in Frostproof Closet Valves; and I do hereby declare the following to be a full, clear, and exact description of the invention, such as will enable others 10 skilled in the art to which it appertains to make and use the same.

My invention consists in the novel features hereinafter described, reference being had to the accompanying drawing, which illustrates 15 one embodiment of the invention selected by me for the purpose of illustration, and the said invention is fully disclosed in the following description and claims.

My present invention is an improvement 20 on the type of apparatus disclosed in my former Patents Nos. 1,034,789, granted August 6, 1912, and 1,111,744, granted September 29, 1914.

The type of apparatus to which my invention applies, is what is termed in the art a frost-proof or anti-freezing water closet valve mechanism, a portion of the valve mechanism being located in the ground below the freezing line and provided with a 25 drain pipe communicating from the valve mechanism to the soilpipe or sewer for draining the service pipe to the closet after the flushing of the closet so as to prevent the pipe from being destroyed by the freezing 30 of water therein. The specific form of the device herein shown is intended to be used with a closed flush tank for accumulating water in said tank when the seat is depressed and on the release of the seat, closing 35 the inlet from the main or service pipe and discharging the accumulated water from the tank to the closet bowl for flushing purposes. Devices of this character are ordinarily installed in outhouses and other places where 40 needed and are connected directly to a water main which in most cases also supplies water to the adjacent house or houses for drinking purposes and the like. It is easily possible under such circumstances for the soilpipe to 45 become clogged so that the water will back up in the soilpipe and bowl, and by reason of the drain pipe connection between the soilpipe and valve mechanism, and the flush pipe connection between the bowl and valve 50 mechanism, or both, the valve casing, or in other words, that part of the apparatus be-

tween the submerged water main and the bowl, may become filled with contaminated water which may be forced back into the main by the air pressure in the tank, or 60 otherwise, upon the opening of the water inlet valve a sufficient distance to find its way to an adjacent hydrant, sink or other apparatus for delivering drinking water, and thus produce sickness and possible loss 65 of life. In the construction shown in my former Patent No. 1,034,789, I provide a check valve between the drain pipe and the valve casing to prevent the contamination of the water through the drain pipe, but 70 further investigation of the subject showed me that contamination of the water in the main might take place through the flush pipe under certain circumstances, and in my Patent No. 1,111,744, I provide a check 75 valve between the main and the water inlet valve of the apparatus below the connection of the drain pipe for the purpose of preventing the possibility of contamination. While this construction has given good re- 80 sults in the main, I have found in actual experience that this construction is open to a serious objection for the reason that it is impossible to repair or replace the check valves without digging up and removing the 85 entire valve mechanism, which extends several feet below the ground, for the purpose of having the connection with the water main well below the frost line. Moreover, in the construction covered by my former 90 Patent No. 1,111,744, there were three valves to be kept in operative condition. According to my present invention, I provide the central valve actuating rod at its lower end with a combined cut off and check valve, 95 permanently, but movably, connected thereto, thereby reducing the number of valves to two, and providing a construction in which, by simply unscrewing a single threaded part at the upper end of the valve 100 casing, the entire valve actuating rod may be removed from the casing so that both valves, including the combined check and cut off valve, can be readily repaired or replaced, as may be necessary.

In the drawing, in which I have shown the best form in which I have contemplated embodying this invention, selected by me for purposes of illustration,

Fig. 1 is a vertical sectional view of a 110 frost proof flushing valve mechanism embodying my invention, intermediate por-

tions being broken away and the parts being illustrated in normal positions.

Fig. 2 is a similar view illustrating the positions occupied by the parts when the seat is depressed, the flushing valve closed, and the combined inlet and check valve open to permit the filling of the tank.

Fig. 3 is a detail sectional view of the lower portion of the valve mechanism showing the check valve seated after the filling of the tank, while the valve stem itself remains in raised position.

Fig. 4 is a detail sectional view, slightly enlarged, showing the manner of connecting the combined check and inlet valve with the valve stem.

In the drawings, 1, represents the upper or main valve casing, provided with a central partition, 2, dividing it into an upper 20 chamber, 3, and lower chamber, 4. The upper chamber is provided with a passage, 5, which I term the flushing passage, and which is connected to the closet bowl, a portion of which is indicated at 6. I conveniently provide this passage, 5, with a bearing portion, 7, and a hinge pin, 8, upon which the seat is hinged. 9 represents a portion of the seat hinge member, secured to the seat, which is here shown broken away, 30 and this hinge member is preferably provided with bifurcated extensions, one of which is indicated at 10, for automatically elevating the valve stem when the seat is depressed. The lower portion of the valve casing, 1, is provided with a threaded aperture, 11, connected by means of a pipe, 12, to a closed flushing tank (not shown) in a well known manner. The partition, 2, is provided with an internally screw threaded 40 aperture, into which is screwed a sleeve, 13, provided at its lower end with a valve seat, 14, within the lower chamber, 4, of the valve casing, and provided above the partition with lateral apertures, indicated at 15, communicating with the flushing passage, 5. The sleeve is provided above the valve casing with a shoulder, 16, to engage a packing washer, 17, and the upper end of the sleeve is provided with an aperture, 18, for the 50 passage of the valve stem, and a stuffing box, 19, surrounding the stem to make a water tight connection. The lower end of the valve casing, 1, is provided with a threaded aperture, 20, into which is screwed the upper 55 end of a long pipe section, 21, extending below the surface of the ground far enough to be well below the surface of the frost line. At the lower end of the pipe, 21, is an auxiliary valve casing, 22, which is preferably screwed on to the lower end of the pipe. This valve casing, 22, is provided at its lower end with a threaded portion, 23, to which is screwed pipe, 24, which supplies the water for the installation, and is connected to the general system of water sup-

ply. It is the water in this pipe which it is the aim of my invention to prevent under every possibility from contamination in order to prevent the possibility of contaminated water being drawn into neighboring 70 service pipes. The valve casing, 22, is provided at its lower end with a valve seat, 25, above which, and within the casing, extends the central bore or passage, 26, in axial alignment with the valve stem. The valve 75 casing is also provided with a lateral bypass, 27, extending from the valve seat, 25, around the passage, 26, and communicating at its upper end with the vertical pipe, 21. The passage, 26, is provided with a lateral 80 outlet passage, 28, which is connected in any suitable manner with a pipe, 29, extending to the soil-pipe of the closet bowl, or any other part of the neighboring sewer connections, for the purpose of draining any water 85 within the valve mechanism after a flushing operation. 30 represents the valve stem, which is preferably formed in sections and united by threaded connections in the usual manner. At the lower end of the valve stem, 90 I provide a plunger, indicated at 31, and shown in section in Fig. 4, the lower portion of the plunger being made to fit the central passage, 26, in the lower valve casing and having its exterior provided with a reduced portion, indicated at 32, which in the normal position of the parts, will be adjacent to the lateral drain passage, 28. The plunger, 31, is bored out at both ends, as shown, leaving a central partition, 33, provided with a reduced aperture through which extends a coupling screw, the lower end of which is threaded into the upper end of the combined inlet and check valve, 35, the lower end of 95 which is provided with a washer, 36, held in place by screw, 37, and adapted to engage the valve seat, 25. The upper end of the plunger, 31, is internally threaded and screwed onto the lower end of the valve stem, 30. It will be seen that the plunger, 100 110 115 120 125 130 31, can be raised without lifting the valve, 35, which has a limited movement vertically with respect to the plunger and valve stem, 30. The valve, 35, is provided with an annular shoulder, 38, which is engaged by the lower end of the plunger, 31, when the parts are in normal position, so as to hold the combined check and inlet valve firmly on its seat. Adjacent to its upper end the valve stem, 30, is provided within the chamber, 4, of the valve casing, 1, with a flushing valve, 39, provided with a washer, 40, for engaging the valve seat, 14, at the lower end of the sleeve, 13. A heavy coil spring, 41, surrounds the valve stem within the sleeve, 13, and between the top portion of the valve sleeve and the washer, 40, and serves to depress the valve stem so as to hold the flushing valve open and the inlet valve closed, as indicated in Fig. 1. The upper end of 130

the valve stem above the valve casing, 1, is provided with a suitable cap, indicated at 42, secured in position by means of a nut, 43, engaging a threaded portion of the valve stem, the said cap engaging the bifurcated arms, 10, of the said hinge member. By virtue of this construction the coil spring, 41, also serves to maintain the seat in raised position, and the depression of the seat will obviously raise the valve stem so as to close the flushing valve and raise the plunger, 31.

The construction of the apparatus having now been described, I will briefly explain the operation of the apparatus. Supposing the apparatus to be in the position shown in Fig. 1, the depression of the seat will rock the hinge member, 9, and raise the valve stem, as before described, thus closing the flushing valve, 39—40, and raising the plunger, 31, into the position shown in Fig. 2, so as to close the drain passage, 28, leading from the central passage, 26. The lifting of the valve stem does not of itself raise the inlet valve. The inlet valve, 35—36 is raised by the water pressure in the main into the position shown in Fig. 2, and the water from the main, 24, will flow upward through the by pass, 27, to the chamber, 4, in the main valve casing, and thence to the tank, accumulating in the tank until the pressure within the tank equals the pressure in the main, when the flow of water will cease and the pressure being equalized, the check valve will drop by gravity into the position indicated in Fig. 3, so as to close the inlet aperture in the lower valve casing. It will thus be seen that no water which has once passed into the valve apparatus can find its way back into the main to contaminate the water therein. When the seat is released, the spring, 41, will cause it to lift and will also depress the valve stem, opening the flushing valve, 39—40, and the air pressure in the tank will cause the accumulated water therein to flow through the pipe into the chamber, 4, of the valve casing, 1, up through the sleeve, 13, and out through the flushing passage, 5, to the bowl, to effect the flushing operation. At the same time the plunger, 31, will descend and open the drain passage, 28, and by engaging the shoulder, 38, on the combined inlet and check valve, will apply the pressure of the spring to this valve to hold it firmly on the seat, 25. There will be a slight leakage of water through the passage, 28, during the flushing operation, but the passage is so much smaller than the flushing passage that its effect is immaterial. When the flushing action is completed, there will remain necessarily a considerable quantity of water in the upper valve casing, the lower valve casing and the connecting pipe section, 21, which, if allowed to remain, would freeze

and destroy the apparatus. This water will drain out through the passage, 29, to the soil pipe and pass off, leaving all that part of the apparatus above the frost line empty so that there is no danger of freezing even in the coldest weather, no matter how frequently or infrequently the apparatus is used. It will also be seen that in case of the contamination of the water within the valve mechanism either through the connection, 29, with the soil pipe, or through the flushing passage, 5, this contaminated water cannot, under any circumstances, pass into the main so as to contaminate the water therein, because the inlet valve is only opened by the actual excessive pressure in the main while it acts exactly as a check valve to instantly close as soon as the pressure in the valve apparatus equals or exceeds that in the main.

It will be readily seen that there are practically only two valves in this mechanism which require repair or attention, the flushing valve, 39—40, and the combined inlet and check valve, 35—36, at the lower end of the valve stem. It will also be seen that by simply unscrewing the sleeve, 13, the entire valve stem, no matter how great its length, can be removed without disturbing any of the pipe connections, thus affording an opportunity to readily repair the valve by replacing the washers, 40 and 36, or otherwise, and the parts can as readily be reassembled in operative position.

While as a matter of convenience the valve casing is preferably made up of an upper valve casing, 1, a lower valve casing, 22, and the connecting pipe, 21, of any desired length, I consider that these parts constitute in reality the valve casing, and in the following claims this term will be understood as applying to these parts, unless otherwise stated.

In providing the flushing valve, 39, with the valve washer, 40, of leather, rubber, fibre or other suitable material I preferably merely slip an annular washer, 40, over the stem and preferably provide above it an ordinary metallic washer, 40^a, of brass or other suitable metal against which the lower end of the spring, 41, abuts. It will thus be seen that the spring, 41, holds the washer, 40, at all times against the face of the metallic valve body, 39. This obviates the necessity of threading the valve stem and providing a securing nut and lock nut, and this materially reduces the cost of manufacture.

What I claim and desire to secure by Letters Patent is:—

1. In a frost proof flushing valve mechanism, the combination with a valve casing, provided at its upper end with a tank connection and a flushing passage, and having a portion adapted to extend below the frost line and provided with a drain passage, and a water inlet, of a vertically disposed valve

- stem mounted in the valve casing and provided adjacent to its upper end with a normally open valve for closing the communication between the tank connection and flushing passage and capable of limited upward movement into closed position, and provided at its lower end with a normally closed combined inlet and check valve for the water inlet, secured to but having a vertical movement with respect to the valve stem, the limited normal movement of the valve stem to close said normally open valve being insufficient to open said combined inlet and check valve.
15. 2. In a frost proof flushing valve mechanism, the combination with a valve casing, provided at its upper end with a tank connection and a flushing passage, and having a portion adapted to extend below the frost line and provided with a drain passage, and a water inlet, of a vertically disposed valve stem mounted in the valve casing and provided adjacent to its upper end with a normally open valve for closing the communication between the tank connection and flushing passage and capable of limited upward movement into closed position, and provided at its lower end with a normally closed combined inlet and check valve for the water inlet, secured to but having a vertical movement with respect to the valve stem, said inlet and check valve and said stem being provided with portions adapted to be brought into contact when the valve stem is in normal position to hold said valve firmly seated, and a spring for holding the valve stem in normal position, the limited normal movement of the valve stem to close said normally open valve being insufficient to open said combined inlet and check valve.
30. 3. In a frost proof flushing valve mechanism, the combination with a valve casing, comprising an upper casing provided with a partition having a threaded aperture therein, a tank connection below said partition and a flushing passage above said partition, a removable sleeve threaded into said partition and provided with portions for closing the upper end of the casing, the lower end of said sleeve being provided with apertures above the partition communicating with the flushing passage and having a valve seat at its lower end below said partition, the lower portion of the valve casing being provided with a water inlet having a horizontal valve seat surrounding the same, a main passage in axial alignment with said seat, a by-pass extending around said main passage, and a drain passage connected with the main passage, of a valve stem extending vertically through said casing and sleeve, and provided with a normally open valve below the valve seat thereof, said valve stem being provided with a plunger engaging the main passage adjacent to said drain passage, and provided
- below the same with a normally closed combined inlet and check valve engaging the valve seat of the water inlet and connected to the valve stem by means permitting said stem to move upwardly, independently thereof, the parts being so constructed that the normal movement of the valve stem to close said first mentioned normally open valve upon the seat at the lower end of the sleeve, will not lift the inlet valve from its seat, and a spring engaging said valve stem and pressing it normally downward into contact with the combined inlet and check valve to hold the latter normally upon its seat, whereby said sleeve may be removed and the valve stem may be bodily withdrawn from the valve casing, together with the valves connected thereto, including the combined inlet and check valve.
4. In a frost proof flushing valve mechanism, the combination with a valve casing comprising an upper casing provided with a partition having a threaded aperture therein, a vertical pipe section connected with said upper casing, and provided with an inlet pipe connection and inlet valve seat at its lower end, of a valve stem extending vertically through said casing and pipe section, a sleeve screwed into the threaded aperture of said partition in the upper casing and guiding said valve stem, said sleeve being provided with a valve seat at its lower end and with apertures communicating with the flushing passage, a normally open flushing valve body on said stem for engaging the lower end of the sleeve, an annular valve washer loosely engaging said valve stem and supported upon the flushing valve body, an inlet valve carried by the lower end of the valve stem, and a coil spring surrounding said stem, having its upper end engaging a part connected with the casing and its lower end engaging said valve washer for normally holding the flushing valve in open position and the inlet valve in closed position, said spring serving at all times to hold said valve washer in operative engagement with the flushing valve body.
45. 5. In a frost proof closet flushing valve, the combination with a casing provided with a tank connection and a flushing passage and having a portion extending below the frost line and provided with a drain passage and a water inlet, of a flushing valve seat and an inlet valve seat, a valve rod reciprocally mounted in the casing and having a valve to engage the flushing valve seat and a combined inlet and check valve carried by said valve rod and adapted to engage said inlet valve seat.
60. 6. In a frost proof closet flushing valve, the combination with a casing provided with a tank connection and a flushing passage

- and having a portion extending below the frost line and provided with a drain passage and a water inlet, of a flushing valve seat and an inlet valve seat, a valve rod reciprocally mounted in the casing and having a valve to engage the flushing valve seat, a combined inlet and check valve carried by said valve rod and adapted to engage said inlet valve seat, and removable means carried by the casing for guiding the valve rod, said means when removed permitting the removal of the valve rod and the flushing and combined inlet and check valve.
7. In a frost proof closet flushing valve mechanism, the combination with a valve casing, of a valve stem removably mounted therein, a flushing valve carried thereby,
- 5 and a mechanically and pressure actuated valve adapted to control the inlet to the casing and being removable from the casing 20 with the valve rod.
8. In a frost proof closet valve, the combination with a valve casing of a valve rod removably mounted therein, a flushing valve carried by the rod and an inlet valve carried 25 by the rod and removable from the casing with said rod, said inlet valve being freely movable with relation to the rod within limits and being seated by actuation of the rod, and unseated by fluid pressure in the casing, 30 and adapted to be reseated when the fluid pressure is balanced.

In testimony whereof I affix my signature.
PHILIP HAAS.
